UNITED STATES PATENT OFFICE.

JAMES REES, OF PITTSBURG, PENNSYLVANIA.

ADJUSTABLE CUT-OFF FOR ENGINES.

SPECIFICATION forming part of Letters Patent No. 392,460, dated November 6, 1888.

Application filed October 21, 1887. Serial No. 253,035. (No model.)

To all whom it may concern:

Be it known that I, JAMES REES, of Pittsburgh, in the county of Allegheny and State of Pennsylvania, have invented a new and useful Adjustable Cut-Off for Steam-Engines; and I do hereby declare the following to be a full, clear, and exact description thereof.

My invention relates to an improvement in "adjustable cut-offs" for steam-engines, the same being an improvement on the adjustable cut-off for which Letters Patent of the United States No. 114,601 were granted to me May 9, 1871. I will proceed to describe in detail and clearly point out in the claims the several improvements of my present invention.

In the accompanying drawings, which form part of my specification, Figure 1 is a top view of the adjustable cut-off. Fig. 2 is a side elevation representing the position of the several parts of the cut-off when the engine is working with full open ports, commonly called "full-stroke." Fig. 3 is a side elevation representing the several parts of the same when in position for cutting off. Figs. 4, 5, 6, 7, and 8 are detail views.

For the purpose of clearness of description and easy comprehension of my present improvement over my former invention described in the hereinbefore-mentioned Letters Patent, I will use the letters of reference in the drawings of said mentioned Letters Patent for corresponding parts in my present improvement.

The desideratum in engines having a "cut-off" is a cut-off susceptible of quick adjustment while the engine or engines is or are in motion to cut off at any point of the stroke, simple and positive in its action, and always under easy control of the engineer. It must also be capable of cutting off at any point from the commencement to the end of the stroke, either in going ahead or "backing," and must also be so arranged as to be instantly thrown out of gear to allow the steam to be worked full stroke, if desired, and of easy adaptation to existing styles of engines, particularly such as are used on steamboats on the Western rivers.

After an experience dating from the date of my aforesaid Letters Patent to the present time in efforts to simplify the invention there-

in described and make it meet the requirements above stated, I have accomplished that desired result by arranging the sliding frame B, which carries the incline-blocks r, upon ways or bearings B' B', so as to be elevated or depressed in columns A' A' through the medium of the sliding bar C, having inclines F', and operated by means of a lever, D', which may have cords attached to its arms L, leading to the throttle-valve, where they may be within easy reach of the engineer.

By comparing my present invention with that described in the before-cited patent it will be observed that the essential features of my present improvement consist in the arrangement of the bearings or ways B' B' in the columns A' A' and elevating or lowering the frame B through the medium of the bearings or ways B' B', which are operated by the sliding bar C, having inclines F' F', said sliding bar being operated through the medium of the lever D'. The disks d' are keyed fast to the forward rock-shaft g, to which are attached the lifters d d and b b, for operating the inlet-valves. Between the two disks is the arm e⁴, working loosely on the shaft g, and to which are attached by pin-joints the pawls S S, which engage the edges of the shoulders S' S' on the disks i' for the purpose of lifting the inlet-valves. The arm e² receives its motion through the medium of the link e³ and arm e⁴ on the rock-shaft, which receives its motion from the ordinary full-stroke cam. This motion being communicated through the above-mentioned parts to the disks d' d', the inlet-valves are opened and held open until the incline-blocks r on the sliding frame B are brought in contact with the lugs x x of the pawls S S, thus releasing them from the shoulders S' S' of the disks i' and allowing the inlet-valves to close, the point of closing being regulated by adjusting the incline-blocks r by right and left hand screws y through the medium of the hand-wheel y' of the sliding frame B, which receives its motion through a reducing-lever, E, from the pendulum f³ and connecting-rods f, which in turn receives its motion from the cross-head n' of the engine. By separating the blocks r the steam will be cut off earlier in the stroke, and by bringing them closer to-

gether the opposite effect will be produced. When it is desired to throw the cut-off out of gear and work steam full-stroke, the sliding frame B, carrying the incline-blocks r, is lowered by moving the bar C' endwise, which allows the ways B' B' of the frame B to move down in the columns A' A', thus allowing the incline-blocks r to move under the lugs x x of the pawls S S of the disks i'.

10 I do not confine myself to the position of the arm e' and pawls S S and disk i' on the shaft g between the disks d' d', as said arm, pawls, and disk i' may be arranged on the outer end of said shaft, if so desired, with the sliding frame B, its ways and elevating and depressing bar being arranged accordingly.

Having thus described my improvement, what I claim in my present improvement is—

1. A pair of pawls, S S, loosely pivoted to the arm e', the said pawls alternately engaging shoulders S' S' on the disk i', in combination with a reciprocating bar and adjustable tripping and disengaging devices for engaging and disengaging the pawls before the end of the stroke, substantially as herein described, and for the purpose set forth.

2. A pair of trippers, r r, adjustably arranged on a reciprocating frame susceptible of elevation and depression, in combination with the pawls S S and engaging-lugs x x, substantially as herein described, and for the purpose set forth.

3. In combination with the vertically-adjustable and reciprocating frame B, the trippers r r, and screw y, whereby the tripper may be adjusted and engaged or disengaged with the lugs x x of the pawls S S by a single motion, substantially as herein described.

4. The combination of the lever D', sliding bar C', ways or bearings B' B', reciprocating frame B, having adjustable trippers r r, and pawls S S, having lugs x x, substantially as herein described, and for the purpose set forth.

In testimony whereof I have hereunto set my hand this 12th day of October, A. D. 1887.

JAMES REES.
